(57) CLAIM

We claim the ornamental design for a trash can lid with slideable elbow-openable access door, as shown and described.

DESCRIPTION

FIG. 1 is a perspective view of a trash can lid with slideable elbow-openable access door showing our new design;

FIG. 2 is a top plan view thereof;

FIG. 3 is a front elevational view thereof;

FIG. 4 is a right side elevational view thereof, the left side elevational view being a mirror image thereof;

FIG. 5 is a rear elevational view thereof; and,

FIG. 6 is a perspective view showing the trash can lid with slideable elbow-openable access door in use; the broken lines depict environmental structure for illustrative purposes only and form no part of the claimed design.

All views show the door partially opened.
